UNITED STATES PATENT OFFICE

147,513

DESIGN FOR A HELICOPTER TOY

Thorne F. Stout, Dayton, Ohio, assignor to Ogden Manufacturing Company, Dayton, Ohio, a corporation of Ohio

Application March 6, 1946, Serial No. 127,157

Term of patent 7 years

(Cl. D34—15)

To all whom it may concern:

Be it known that I, Thorne F. Stout, a citizen of the United States, residing at Dayton, Montgomery County, Ohio, having invented a new, original, and ornamental Design for a Helicopter Toy, of which the following is a specification, reference being had to the accompanying drawing, forming a part thereof, in which

Fig. 1 is a side view of a helicopter toy embodying my new design, and Fig. 2 is a front view thereof.

The present toy comprises a fuselage portion on the top of which is mounted a pair of wing members disposed in vertically spaced planes parallel with the axis of the fuselage portion. The opposite side of the toy is substantially identical in appearance with that shown in Fig. 1,

and the bottom of the toy is substantially plain.

I claim:

The ornamental design for a helicopter toy, substantially as shown and described.

THORNE F. STOUT.
